A. E. BLACKMAN

RADIATOR COVER

Filed Dec. 10, 1925

Inventor

Albert Edgar Blackman

By his Attorney

Emanuel Scheyer.

UNITED STATES PATENT OFFICE.

ALBERT EDGAR BLACKMAN, OF MOUNT VERNON, NEW YORK.

RADIATOR COVER.

Application filed December 10, 1925. Serial No. 74,564.

My invention relates to radiator covers in the form of a box which is adapted to be stood over and completely envelop a radiator of that class which is used for heating rooms of buildings by steam or hot water. One of the principal objects of my invention is so to construct the cover that its cost of manufacture will be at a minimum and at the same time it will be ornamental in appearance. Another object is the provision of a sufficient number of doors in the cover so that no special care need be exercised, in ordering covers for a particular installation, to determine which side the valves of the radiator are located. It has been found in practice, that where a radiator cover is used with only one or two doors for the radiator valves, errors are constantly made as to which side of the radiator the valves are located so that when the cover is finally put in place the doors are not in such position as to make the valves accessible. A still further object is the provision of a bracket below each door for holding a humidifier. The extra doors provided are especially useful with humidifiers in that those doors which are not opposite a valve can be used for the insertion of humidifiers. Features of the radiator cover shown herein but not claimed, form the subject matter of my co-pending application Serial No. 747,228, filed November 1, 1924.

In the drawings: Figure 1 is a longitudinal section of the radiator cover, Fig. 2 is a cross-section taken along the line 2—2 of Fig. 1, Fig. 3 is a section taken along the line 3—3 of Fig. 1, Fig. 4 is a perspective view of a hinge for the door and Fig. 5 is a perspective view of a humidifier used for holding a quantity of water.

The radiator cover is preferably made of sheet metal, pieces 10 and 11 forming the sides, piece 12 the back and piece 13 the top. Pieces 10 and 11 are formed with flanges at the back to the inside of which back 12 is welded. Perforated front 14 is held in place between angles 25 welded to the inside of sides 10 and 11, and the front flanges of said sides. Top 13 is welded to the top of sides 10 and 11 and back 12.

There are four openings provided each with a hinged door 16. This allows the cover to fit the valves of the radiator, 23 being the usual air valve and 26 the usual inlet valve for steam, whether they are located as

shown in Fig. 1 or whether they are located opposite hand to that shown. An additional valve (not shown) such as 26 is provided on some types of radiators on the other side of the radiator from the valve 26 shown in Fig. 1. Below each opening for a door 16, a bracket 21 is provided. These brackets are formed with a pocket 27 into which is adapted to be slid lip 22 of the humidifier 24.

Each door 16 is provided with a U-shaped hinge 17 having hook shaped legs near the outer end of which is provided a hole 19. Hinges 17 are pivotally mounted through holes 19 between angles 18 welded to the inside of sides 10 and 11. The form of the legs of hinges 17 is such that as the door swings open, the concave portion of said legs is adapted to clear the edge of the opening as clearly shown in Fig. 3 for the left hand door. A spring catch 20 is provided for each door for holding it closed.

I claim:

1. A radiator cover having a plurality of openings, a humidifier for moistening the heated air arising from said radiator, said openings being provided for obtaining access to the radiator valves and for the introduction of the humidifier within the cover, a plurality of doors for closing said openings, and brackets for supporting the humidifier fastened to the cover near each opening whereby said cover is adapted to support the humidifier in one position or another to avoid the valves of radiators having valves in different positions.

2. A radiator cover having an opening, a humidifier for moistening the heated air arising from said radiator, said opening being provided for obtaining access to the radiator valve and for the introduction of the humidifier within the cover, a bracket fastened to the inside of the cover below said opening, said bracket being provided with a pocket for engaging with and supporting the humidifier.

3. A radiator cover having a plurality of openings, a humidifier for moistening the heated air arising from said radiator, said openings being provided for obtaining access to the radiator valves and for the introduction of the humidifier within the cover, said cover being adapted to support the humidifier near each of said openings, whereby the humidifier can be introduced into the cover through one opening or another into

its supported position without interference with the valves of radiators having valves in different positions.

4. A radiator cover having an opening, a humidifier for moistening the heated air arising from said radiator, said opening being provided for obtaining access to the

radiator valve and for the introduction of the humidifier within the cover, a bracket mounted upon the inside of the cover near said opening adapted to support said humidifier. ¹⁰
